MACHINE-SWITCHING TELEPHONE SYSTEM.

1,413,368.

Specification of Letters Patent. Patented Apr. 18, 1922.

Application filed November 19, 1919. Serial No. 339,026.

To all whom it may concern:

Be it known that I, SAMUEL B. WILLIAMS, Jr., a citizen of the United States, residing at Brooklyn, in the county of Kings and State of New York, have invented certain new and useful Improvements in Machine-Switching Telephone Systems, of which the following is a full, clear, concise, and exact description.

10 This invention relates to machine switching telephone systems of the type in which talking current is supplied to the talking conductors through impedance coils, and more particularly to circuits for impulse and 15 supervisory relays in such systems.

It is the object of this invention to provide, in such a system, a circuit arrangement whereby a relay connected in series with the talking conductors may be made 20 responsive to short interruptions of the current in said conductors and may also be used as a supervisory relay without impairing the transmission of voice current.

25 A feature of the invention is the connection of a capacity element in parallel with the source of talking current during the time that the series relay is to be responsive to impulses, and the removal of this element when this relay no longer needs to respond 30 to impulses.

The drawing shows the invention applied to a telephone system using transmission of the repeating coil type, but it is obvious that it is equally applicable to systems using any 35 other type of transmission in which talking current is supplied through impedance coils.

To the left of the dotted line are shown 40 diagrammatically the substation 1 of a calling line, a line switch indicated by brushes 3, 4, and 5 and a first selector switch of the step-by-step type. On the right of the dotted line a connector switch and a called line are shown. The substation of the calling line is equipped with an impulse sender 2, 45 which may be of any type which causes circuit changes of short duration when operated.

A subscriber at 1 desiring to initiate a call removes his receiver from its hook, thereby 50 operating the line switch to extend the calling line through brushes 3, 4 and 5 to the terminals 6, 7 and 8 of an idle selector switch. A circuit is thereupon completed from grounded battery through the lower

left-hand winding of repeating coil 9, winding of impulse relay 10, terminal 7, brush 4 through the calling line including the apparatus at station 1, brush 3, terminal 6, upper left-hand winding of repeating coil 9 to ground. Relay 10 is energized in this circuit and in attracting its armature energizes slow release relay 11. Relay 11, in attracting its inner armature, interposes a break in the circuit of the release magnet and prepares a path for impulses to operate stepping magnets. In attracting its outer armature, relay 11 connects ground to terminal 8 to hold the line switch operated and to render the multiples of the selector switch in other line switch banks 55 60 65 70 75 80 85 90 95 100 105

busy. The subscriber now operates his impulse sender 2 to send the hundreds series of impulses. The sender 2 in restoring interrupts the circuit traced for impulse relay 10 a number of times corresponding with the hundreds digit of the called line. In response to the first interruption of its circuit relay 10 retracts its armature completing a circuit from ground, armature and back contact of relay 10, inner armature and front contact of relay 11, back contact and right-hand armature of relay 12, through the winding of relay 13, side switch arm 14 (position 1) through the winding of primary magnet 15 to grounded battery. Magnet 15 is energized in this circuit and steps selector brushes 16, 17 and 18 one step in their primary direction. Slow release relay 13 is also energized in this circuit and being slow to release will remain energized throughout each series of impulses. In attracting its armature, relay 13 completes a circuit from ground, front contact and armature of relay 13, arms 19 and 20 (position 1), through the winding of escape magnet 21 to grounded battery. Magnet 21 is energized in this circuit but does not operate the side switch until it is deenergized.

When the selector switch is idle the condenser 22 is connected across the talking conductors through arm 23 and is charged to the full potential of the battery. If condenser 22 were not connected across the line the relay 10 would deenergize upon the first interruption of the line circuit caused by the operation of the impulse sender, but at the close of this interruption, owing to the impedance of the repeating coil and of the

winding of relay 10, current would build up slowly in the line circuit and would not reach a sufficient value to operate relay 10 before the next interruption caused by the 5 sender. With the condenser 22 connected as shown, however, at the end of each interruption of the line circuit a discharge circuit for condenser 22 is completed from the right-hand plate of the condenser 22, arm 23, 10 winding of relay 10, terminal 7, brush 4, substation 1, brush 3, terminal 6, to the left-hand plate of condenser 22. Since the impedance of this path is relatively much lower than that of the circuit through the repeating coil 9, condenser 22 discharges rapidly, thereby adding its discharge to the normal current, thus quickly building up the current through the winding of relay 10 to a sufficient value to operate said relay. During 20 the interruption of the line circuit, condenser 22 is recharged. Thus by the connection of a condenser in parallel with repeating coil 9, relay 10 is made responsive to short interruptions of the line circuit, the 25 effect of which would merely be to cause it to hold its armature retracted throughout such impulses if condenser 22 were not connected across the line.

Relay 10 vibrates its armature in response 30 to the remaining impulses of the hundreds series, holding slow release relay 13 energized and operating magnet 15 to step brushes 16, 17 and 18 to the desired group of lines. At the conclusion of this series of impulses, relay 10 remains energized and after a short interval relay 13 retracts its armature to open the circuit of escape magnet 21 which thereupon is deenergized to move the side switch arms to their second position. A 35 circuit is immediately completed from grounded battery through the winding of magnet 21, arm 20 (position 2), conductor 24, secondary off-normal contact 25 to ground. Magnet 21 in attracting its armature completes a circuit from grounded battery through the winding of secondary magnet 26, armature and back contact of said magnet, front contact and armature of magnet 21, arm 27 (position 2), outer armature 40 and front contact of relay 11 to ground. Secondary magnet 26 is energized in this circuit to step brushes 16, 17 and 18 into engagement with the first set of terminals in the selected group, thereby opening off-normal contact 25 and interrupting the circuit 45 for escape magnet 21. If this set of terminals is busy, ground potential will be present on its test terminal 29 and will be extended through brush 18, conductor 24, arm 20 (position 2), through magnet 21, to 50 grounded battery, to hold magnet 21 energized. Secondary magnet 26 in attracting its armature makes and breaks its circuit, stepping brushes 16, 17 and 18 over the 55 group of terminals until an idle set 64, 28

and 29, distinguished by absence of ground on test terminal 29, is reached. At this time there is no longer a circuit for magnet 21, which is deenergized, to pass the side switch arms to their third position. A circuit is 70 now completed from ground, front contact and outer armature of relay 11, conductor 30, arm 27 (position 3), conductor 24, brush 18, terminal 29, left-hand armature and back contact of connector release magnet 31, arm 75 32 (position 1), through the winding of relay 33 to grounded battery. Relay 33 is energized in this circuit. In attracting its outer right-hand armature relay 33 prepares a path for the tens and units impulses and 80 in attracting its left-hand armature relay 33 interposes a break in the circuit of release magnet 31.

The calling subscriber now operates his impulse sender to send a series of impulses 85 corresponding to the tens digit of the called line. Relay 10, as before, vibrates its armature in response to these impulses, at each retraction of its armature completing a circuit from ground, armature and back contact of relay 10, inner armature and front contact of relay 11, back contact and right-hand armature of relay 12, through the winding of relay 13, arm 14 (position 3), brush 16, terminal 64, conductor 34, outer 90 right-hand armature and front contact of relay 33, arm 35 (position 1) through the winding of connector primary magnet 36 to grounded battery. Magnet 36 in response to the intermittent completion of this circuit 95 steps brushes 37, 38 and 39 of the connector switch to the group of terminals containing those of the wanted line. Relay 13 is also energized in the impulse circuit retaining its armature attracted throughout the series of 100 impulses and completing a circuit from ground, front contact and armature of relay 13, arm 19 (position 3), brush 17, terminal 28, arm 40 (position 1), back contact and armature of relay 41 through the winding of connector escape magnet 42 to 105 grounded battery, and in parallel with this circuit from arm 40 through the winding of slow release relay 43 to grounded battery. Escape magnet 42 and relay 43 are energized in these circuits, relay 42 performing 110 no operation at this time, but relay 43 completing a locking circuit for relay 33 which may be traced from grounded battery through the winding of relay 33, inner 115 right-hand armature and front contact of said relay, front contact and left-hand armature of relay 43, terminal 29, brush 18, arm 27 (position 3), conductor 30, outer armature and front contact of relay 11 to ground. At the conclusion of this series of impulses, 120 relay 13 deenergizes to interrupt the circuit for relay 43 and escape magnet 42. Escape magnet 42 is deenergized to advance connector side switch arms to their second position. 125

At the conclusion of this series of impulses, relay 13 deenergizes to interrupt the circuit for relay 43 and escape magnet 42. Escape magnet 42 is deenergized to advance connector side switch arms to their second position. 130

- sition. Relay 43 opens the locking circuit traced for relay 33, but this relay is held energized over a substitute locking circuit which may be traced from grounded battery, through the winding, inner armature and front contact of relay 33, conductor 44, arm 32 (position 2) and thence over the original energizing circuit of relay 33 to ground at the outer armature of relay 11.
- 10 The subscriber now operates his sender 2 to send the units series of impulses. As before relay 10 responds to these impulses, intermittently completing a circuit from ground, armature and back contact of relay 15 10, inner armature and front contact of relay 11, back contact and right-hand armature of relay 12, through the winding of relay 13, arm 14 (position 3), brush 16, terminal 64, conductor 34, outer right-hand 20 armature and front contact of relay 33, arm 35 (position 2) through the winding of secondary magnet 46 to grounded battery. Magnet 46 responds to the intermittent completion of this circuit to step brushes 37, 38 and 39 into engagement with the terminals 25 of the called line. Relay 13 is also energized in the circuit just traced and completes the energizing circuits for escape magnet 42 and slow release relay 43 which 30 are the same as those previously traced with the exception that arm 40 is now in position 2. At the end of this series of impulses relay 13 retracts its armature, interrupting these circuits to deenergize magnet 35 42 which thereby passes the connector side switch arms to their third position. Relay 43, being slow to release, however, maintains the first traced locking circuit for relay 33 until the called line is tested.
- 40 If the called line is busy, ground potential will be present on its test terminal 47, being supplied thereto from ground over the front contact and left-hand armature of test relay 48, arm 49 (position 3), and 45 brush 39 of the connector switch which is in engagement with a multiple of terminal 47, or from ground through the right-hand low-resistance winding of the relay 48, arm 49 (position 4) and brush 39 of such a 50 switch, or if the line is busy as a calling line, from the line or first selector switch in the well-known manner. This ground potential present on terminal 47 shunts test relay 48 and there being no longer any 55 circuit for relay 43, this relay after a short interval retracts its armature to open the locking circuit of relay 33. Relay 33, in deenergizing completes a circuit from grounded battery, left-hand armature and 60 back contact of relay 33, through the winding of release magnet 31 and off-normal contact 50, closed when the brushes took their first step, to ground. Magnet 31 is energized in this circuit to restore the brushes, 65 off-normal contact, and side switch arms of
- the connector switch to their normal position, but before contact 50 opens, contact 51 is closed to complete a substitute holding circuit for magnet 31, which may be traced from grounded battery, left-hand armature and back contact of relay 33, magnet 31, contact 51, resistance 52, front contact and left-hand armature of magnet 31, terminal 29, brush 18, arm 27 (position 3), conductor 30, outer armature and front contact of relay 11 to ground. When the side switch arms reach their normal position arm 54 completes a busy tone circuit from ground through the secondary winding of busy tone source 53, front contact and right-hand armature of magnet 31, arm 54 (position 1), condenser 55, terminal 28, brush 17 arm 19 (position 3), armature and back contact of relay 13, winding of relay 12, through the lower right-hand winding of 70 repeating coil 9 to grounded battery. This tone is repeated to the calling subscriber by induction through the lower left-hand winding of repeating coil 9 and he replaces his receiver on its hook. Relay 10 is thereby deenergized to open the circuit of relay 11. Relay 11 in retracting its inner armature completes a circuit from grounded battery through the winding of selector release magnet 56, contact 57, closed when the selector switch left its normal position, back contact and inner armature of relay 11, back contact and armature of relay 10 to ground. Magnet 56 is energized in this circuit and releases the selector switch. Relay 11 in 75 80 85 90 95 100 105 110 115 120 125 130
- If the called line is found idle, battery potential will be present on its test terminal 47, being supplied through the winding of its cut-off relay and a circuit will be completed through brush 39, arm 49 (position 3) left-hand high resistance winding of relay 48 to ground. The cut-off relay of the called line and relay 48 are energized in this circuit, relay 48 in attracting its left-hand armature shunting its left-hand winding to supply full ground potential to test terminal 47 as previously described. Relay 48 in attracting its right-hand armature completes a locking circuit from ground through its right-hand low resistance winding, right-hand armature and front contact, arm 40 (position 3), through the winding of relay 43, to grounded battery and in parallel with this circuit through the winding of escape magnet 42 to grounded battery. Relay 43 retains its armatures attracted thereby maintaining the locking circuit of relay 33. Magnet 42 in

attracting its armatures completes a ringing circuit from a source of ringing current through the winding of marginal trip relay 41, left-hand armature and front contact of magnet 42, arm 65 (position 3), brush 38 and its associated terminal, through the ringer at the called substation, brush 37 and its associated terminal, arm 58 (position 3), front contact and right-hand armature of magnet 42 to ground. The bell of the called line is rung in this circuit, but relay 41 is marginal and will not be energized until the called subscriber answers. A portion of the ringing current is also transmitted from the source of current through the winding of relay 41, left-hand armature and front contact of magnet 42, conductor 59, arm 54 (position 3), condenser 55 to terminal 28 and thence over the path previously traced for the busy tone to the calling subscriber, who is thereby informed that the called line is being signalled. When the called subscriber removes his receiver from its hook, he lowers the resistance of the ringing circuit to energize relay 41. Relay 41, in attracting its armature, opens the circuit of escape magnet 42, which is deenergized to pass the side switch arms to their fourth position and to cut off ringing current. Arm 40 in passing from position 3 to position 4 interrupts the circuit of relay 43 which is thereupon deenergized. Before retracting its right-hand armature, however, a circuit is completed from ground, front contact and right-hand armature of relay 43, arm 60 (position 4), terminal 28, brush 17, arm 19 (position 3), armature and back contact of relay 18, through the winding of relay 12 and the lower right-hand winding of impedance coil 9 to grounded battery. Relay 12 is energized in this circuit and completes an energizing circuit for magnet 21, from ground, left-hand armature and front contact of relay 12, arm 20 (position 3), through the winding of magnet 21 to grounded battery. Magnet 21 in energizing passes the selector side switch arms to their fourth position. In the fourth position of the connector side switch, relay 33 is held energized from grounded battery, through its winding, inner right-hand armature and front contact, conductor 44, arm 32 (position 4), back contact and left-hand armature of magnet 31, terminal 29, brush 18, arm 27 (position 4), conductor 30, outer armature and front contact of relay 11 to ground. In passing from its third to its fourth position, arm 23 removed condenser 22 from its connection across the calling line and connected a noninductive resistance 61 in parallel with impulse relay 10. This resistance 61 offers a better path for voice current than the winding of relay 10, but is adjusted to allow sufficient current to flow through relay 10 to hold said relay energized and this relay

becomes a supervisory relay controlling release of all the switches employed in building up the connection. With the selector and connector side switches in position 4 a talking circuit is completed between the calling and the called lines over the conductors shown in heavy black, talking current being supplied to the calling line from grounded battery through the lower left-hand winding of repeating coil 9, arm 23 (position 4), resistance 61, terminal 7, brush 4, through the calling substation 1, brush 3, terminal 6 and upper left-hand winding of repeating coil 9 to ground, talking current being supplied to the called line from grounded battery through the lower right-hand winding of repeating coil 9, and thence in parallel through the winding of relay 12 and its non-inductive shunt 62, back contact and armature of relay 13, arm 19 (position 4), brush 17, terminal 28, arm 65 (position 4), brush 38 and its associated terminal, through the called substation, brush 37 and its associated terminal, arm 58 (position 4), terminal 64, brush 16, arm 14 (position 4), arm 63 (position 4), through the upper right-hand winding of repeating coil 9 to ground.

At the completion of the conversation, when the calling subscriber replaces his receiver on its hook, he interrupts the circuit of supervisory relay 10 which, in retracting its armature, opens the circuit of relay 11 and completes the circuit for release magnet 56 in the manner previously described. Relay 11, in retracting its outer armature opens the holding circuit previously traced for relay 33, which in deenergizing closes the previously traced circuit for release magnet 31. The removal of ground potential from terminal 8 also releases the line switch and the apparatus is now completely restored.

Thus it appears that by the connection of a condenser in parallel with the supply of talking current, during the time that switches are being set, a series relay may be made responsive to impulses of short duration regardless of the high impedance of the line circuit caused by the presence in the line of impedance or repeating coils. When the called subscriber responds to the call, the condenser, which would, of course, destroy the talking qualities of the calling loop, is removed from its position across the line and a non-inductive shunt is connected in parallel with the impulse relay to provide a better path for voice current and to enable the impulse relay to be used as a supervisory relay.

What is claimed is:

1. In a telephone system, the combination with a line circuit, an automatic switch, a stepping relay, a non-inductive resistance, and a condenser, of means for including said relay and said condenser in said line circuit, an impulse sender in said circuit for

operating said relay to set said switch, and means for substituting said resistance for said condenser when said switch is set.

2. In a telephone system, the combination 5 of a telephone line, a trunk circuit, means for connecting said telephone line to said trunk circuit, a stepping relay in said trunk circuit, battery feed coils and a source of current connected across said trunk, a circuit including a condenser in parallel with said coils and source of current, an impulse sender in said telephone line to intermittently operate said stepping relay, a called line, means responsive to the operation of said relay for 10 extending said trunk circuit to said called line, and means for thereafter interposing a break in the circuit of said condenser.

3. In a telephone system, the combination 20 of a telephone line, a trunk circuit, means for connecting said telephone line to said trunk circuit, a stepping relay in said trunk circuit, battery feed coils and a source of current connected across said trunk, a circuit including a condenser in parallel with said 25 coils and source of current, an impulse sender in said telephone line adapted to intermittently operate said stepping relay, a called line, means responsive to the operation of said relay for extending said trunk circuit to 30 said called line, a non-inductive resistance, and means operated after the extension of said trunk line to said called line for interposing a break in the circuit of said condenser and for including said non-inductive resistance in shunt of said relay.

4. In a machine switching telephone system, the combination of a telephone line, an impulse sender associated therewith, a trunk circuit in association with said telephone 40 line, a relay in series with said trunk circuit,

a source of current connected to said trunk circuit, impedance coils in series with said source of current to exclude voice currents therefrom, a circuit including a condenser connected across said trunk circuit in parallel with said source of current and impedance coils to render said series relay responsive to the operation of said impulse sender, a called line, means responsive to the operation of said relay for extending said 45 trunk circuit to said called line, means responsive to such extension for signaling said called line, and means actuated by the response of the called subscriber for interposing a break in said condenser circuit. 50

5. In a machine switching telephone system, the combination with, a telephone line, an impulse sender associated therewith, a trunk circuit associated with said telephone line, a relay in series with said trunk circuit, a repeating coil, a source of current connected to said trunk circuit through the windings of said repeating coil, a circuit including a condenser connected across said trunk circuit in parallel with said repeating 60 coil to render said series relay responsive to the operation of said impulse sender, a called line, means responsive to the operation of said relay for extending said trunk circuit to said called line, means responsive to such 65 extension and to the idle condition of said called line for signaling said called line, and means actuated by the response of the called subscriber for opening said condenser circuit and closing a non-inductive path for 70 current in parallel with said series relay. 75

In witness whereof, I hereunto subscribe my name this 17th day of November A. D., 1919.

SAMUEL B. WILLIAMS, JR.
